US0D1028710S

(12) **United States Design Patent** (10) Patent No.: **US D1,028,710 S**
(45) Date of Patent: ** May 28, 2024

(54) **PACKAGING CONTAINER BLANK**

(71) Applicant: **Elopak AS**, Spikkestad (NO)

(72) Inventor: **Gerd Unni Kvam**, Hokksund (NO)

(73) Assignee: **Elopak AS**, Spikkestad (NO)

(**) Term: **15 Years**

(21) Appl. No.: **35/516,095**

(22) Filed: **Jan. 24, 2022**

(80) **Hague Agreement Data**

Int. Filing Date: **Jan. 24, 2022**

Int. Reg. No.: **DM/220397**

Int. Reg. Date: **Jan. 24, 2022**

Int. Reg. Pub. Date: **Jan. 27, 2023**

(51) **LOC (14) Cl.** 09-03

(52) **U.S. Cl.**

USPC **D9/433**

(57) **CLAIM**

The ornamental design for packaging container blank, as shown and described.

DESCRIPTION

1. Packaging container blank

2. Packaging container

3. Packaging container

4. Packaging container blank

5. Packaging container

6. Packaging container

7. Packaging container blank

8. Packaging container

9. Packaging container

10. Packaging container blank

11. Packaging container

12. Packaging container

13. Packaging container blank

14. Packaging container

15. Packaging container
